HAIR CURLER CLIP

Humphrey Statter, New York, N. Y.

Application June 24, 1949, Serial No. 3,520

Term of patent 14 years

(Cl. D86—10)

To all whom it may concern:

Be it known that I, Humphrey Statter, a citizen of the United States and a resident of the city of New York, in the county of New York and the States of New York, have invented a new, original, and ornamental Design for Hair Curler Clip, of which the following is the specification, reference being had to the accompanying drawing, forming part thereof.

I claim:

The ornamental design for a hair curler clip, substantially as shown.

HUMPHREY STATTER.
